UNITED STATES PATENT OFFICE.

WILLIAM SCHICKEL, OF NEW YORK, N. Y., ASSIGNOR TO THE TUTTLE & BAILEY MANUFACTURING COMPANY, OF SAME PLACE.

DESIGN FOR A HOT-AIR-REGISTER FRONT.

SPECIFICATION forming part of Design No. 17,411, dated June 21, 1887.

Application filed November 1, 1886. Serial No. 217,729. Term of patent 14 years.

To all whom it may concern:

Be it known that I, WILLIAM SCHICKEL, a citizen of the United States, residing at New York city, in the county and State of New York, have invented and produced a new and original Design for a Hot-Air-Register Front, of which the following is a specification, reference being had to the accompanying drawing, in which my newly-designed register-front is represented in front elevation or face view.

The design consists of the ornamental configuration of the open fret-work, comprising the central ring, *a*, of slightly-elliptical form, and substantially resembling a horseshoe having the ends joined by a bar at the heel, which ring is ornamented on the face with raised ornaments *b* and on the edge with the beads *c*, and is supported on the vine-shaped stem *e*, and surmounted with flower-shaped ornaments *f* and *g*. From the stem *e*, below the ring, a vine branch, *h*, springs upward laterally each side of and partly over the top of the ring and joins the flower ornaments *f* *g*, and these branches each have another branch, *i*, projecting outwardly across and joining with parallel bars *j*, and also joining the border-frame *k*. The branches *h* bear flowers *l* near the upper end, and above said branches and flowers are

festoons *m*, depending from the parallel bars *j*, and a transverse bar, *n*. The stem *e*, supporting the center figure and branches, springs from the lower transverse bar, *o*, and has branches *p*, also joining said transverse bar. These figures comprise the essential features of the inner field of the design, together with that portion of the margins consisting of the branches *i*, crossing the parallel bars *j*, which, together with the corner figures *q*, flowers *s*, top and bottom scrolls, *t*, and flowers *u*, comprise the marginal field of said designs.

I claim—

1. The design for a register-front, comprising the figures of the inner field—viz., the central ornamented ring, *a*, supporting stem *e*, surmounted flowers *f* *g*, branches *h*, branches *i*, bars *j*, flowers *l*, festoons *m*, and branches *p*—as herein set forth.

2. The design for a register-front, comprising the figures of the marginal field—viz., the branches *i*, parallel bars *j*, corner figures *q*, flowers *s*, top and bottom scrolls, *t*, and flowers *u*—as herein set forth.

WM. SCHICKEL.
